CHILD'S MULTIPLE ELEMENT POP-UP TOY

Frank Kohner, Washington Heights, Anthony N. D'Elia, Riverdale, and Edward M. Stolarz, Yorktown Heights, N.Y., assignors to Kohner Bros., Inc., East Paterson, N.J., a corporation of New York

Filed Apr. 6, 1967, Ser. No. 6,562

Term of patent 14 years

(Cl. D34—15)

FIG. 1

FIG. 2

FIG. 3

FIG. 4

FIG. 5

FIG. 1 is a top plan view of a child's multiple element pop-up toy showing our new design;

FIG. 2 is a front elevational view of said toy;

FIG. 3 is a left side elevational view of said toy;

FIG. 4 is a rear elevational view of said toy; and FIG. 5 is a front perspective view of the toy with the pop-up elements in exposed position.

Conventional legible matter is shown in broken lines.

We claim:

The ornamental design for a child's multiple element pop-up toy, substantially as shown and described.
